(57) **CLAIM**

The ornamental design for combination handsfree device for a handset and charger, as shown and described.

DESCRIPTION

FIG. 1 is a front view of a combination handsfree device for a handset and charger showing my new design;

FIG. 2 is a rear view thereof;

FIG. 3 is a bottom plan view thereof;

FIG. 4 is a top plan view thereof;

FIG. 5 is a right side view thereof;

FIG. 6 is a left side view thereof;

FIG. 7 is a perspective front view thereof;

FIG. 8 is a perspective rear view thereof;

FIG. 9 is a right side view thereof, in an alternate position;

FIG. 10 is a left side view thereof;

FIG. 11 is a front view of a modified embodiment of the design shown in FIGS. 1-10;

FIG. 12 is a rear view thereof;

FIG. 13 is a bottom plan view thereof;

FIG. 14 is a top plan view thereof;

FIG. 15 is a right side view thereof;

FIG. 16 is a left side view thereof;

FIG. 17 is a perspective front view thereof;

FIG. 18 is a perspective rear view thereof;

FIG. 19 is a right side view thereof, in an alternate position; and,

FIG. 20 is a left side view thereof.
